UNITED STATES PATENT OFFICE.

WILLIAM S. JACKSON, OF RIDGEWOOD, NEW JERSEY, ASSIGNOR TO HERMAN B. THURSTON, OF PITTSBURGH, PENNSYLVANIA.

LOW-WATER ALARM.

1,406,024.

Specification of Letters Patent.

Patented Feb. 7, 1922.

Application filed July 14, 1920. Serial No. 396,262.

To all whom it may concern:

Be it known that I, WILLIAM S. JACKSON, a citizen of the United States, residing at Ridgewood, in the county of Bergen and 5 State of New Jersey, have invented a certain new and useful Improvement in Low-Water Alarms, of which the following is a full, clear, and exact description, reference being had to the accompanying drawings.

10 My invention relates to low water alarms of the type wherein fusible means normally closes a steam line leading to an alarm signal, the fusible member melting when the temperature rises to a danger point and 15 thereby sounding the alarm.

One of the objects of my invention is to provide in a low water alarm, means which is adapted not only to sound an alarm but also to extinguish the fire beneath the boiler.

20 A further object of the invention is to provide in a low water alarm a socket member and means thereon normally closing communication between the alarm signal and the interior of the boiler and between 25 the fire box and the interior of the boiler. Under a dangerous increase in temperature both of said closing means cease to function. This opens passages causing the whistle to sound and the fire to be extinguished.

30 A further object of the invention is to provide an effective device of such character wherein the fusible members are interchangeable and removable, and which device is simple, easy to operate and capable 35 of being cheaply made.

In carrying out this invention I employ a fixture having a common passage to which the steam is lead and communicating with a passage leading to the alarm signal, and

40 a passage leading to the fire box, each of the latter passages are closed by a fusible plug. An important feature of my invention is to so construct these plugs that they may be readily removed and replaced and be in- 45 terchangeable from one passage to the other, fitting either passage equally well and without requiring accurate fitting to prevent leakage.

In the accompanying drawings wherein 50 my invention is illustrated Fig. 1 is a side elevation partly broken away showing my invention applied to a boiler; Fig. 2 is an elevation of the socket member, the internal threads being shown in dotted lines; Fig. 3 55 is a section on the line 3—3 of Fig. 2, the

internal plugs being shown in position; Fig. 4 is a plan and Fig. 5 an elevation of the outer plug; Fig. 6 is a plan and Fig. 7 an elevation of the inner plug; Fig. 8 is a plan and Fig. 9 an elevation of a cap for the outer 60 plug; Fig. 10 is an elevation and Fig. 11 is a plan of the fusible stopper.

Referring to the drawings, a boiler of any suitable type is indicated at 1, the crown sheet being shown at 5. A socket member 65 shown at 2 is connected by a pipe 4 to a whistle 6.

The socket member indicated at 2 comprises a hollow bushing like member having the nut 6 adjacent one end thereof. Adjacent the nut, the socket is shown as provided with external tapering threads 10 and above the threaded portion a series of channels 11 furnish means of communication between the exterior of the plug and a chamber 14 75 within the same. Beyond the chamber the socket may be tapered as at 18.

A set of internal tapering threads 20 may be provided adjacent the ends of the socket for engagement with the pipe 4. A channel 80 22 leads from the threaded portion 20 and communicates with a double shouldered portion 23, 24 on the socket member. These shoulders are adapted to form seats for similar shoulders 28, 29 on a fusible member 30 85 adapted to be seated thereon. This fusible member may be made of any suitable material and may be held in place by a plug 40.

The plug 40 has a channel 42 extending therethrough and may have tapering threads 90 44 thereon, fitting similar threads on the interior of the socket 2. A suitable wrench engaging means 46 may be provided on the plug 40.

A second plug 50, having an aperture 51 95 extending therethrough, may be secured by means of tapering threads 52 to the socket member. This plug 50 may be provided with suitable wrench engaging means, in this instance shown as a squared hole 55 for 100 facilitating positioning and removal thereof.

A second fusible plug 30', which may be of the same size as the plug 30, is adapted to be seated adjacent one end of the plug 50 and to be secured in place by means of a cap 105 60 shown as threaded at 57 to the plug 50. The cap 60 is provided with a central aperture 61 aligning with the aperture in the plug 50. The fusible plug 30 is a circular member, comprising two portions 28 and 29 110

of different diameters. The portion 28 of the fusible member may seat in the aperture 61 of the cap and be centered thereby. This construction provides two shoulders which aid in making a tight joint. The fusible plugs 30 and 30' being of the same size are interchangeable so that only the one size need be kept in stock.

To assemble the device a fusible member 10 30 is inserted in an empty casing and a plug 40 is threaded in the opening. Another fusible member, which may be of the same dimensions as the one previously mentioned, is seated on a plug 50 and is secured thereto 15 by the cap 60. It will be noted that by providing the shoulders on the fusible members the latter may be more readily seated and a better bearing surface is provided, thereby assuring a tight joint. After the plugs have 20 been inserted in place the case is ready to be inserted in the crown sheet of the boiler and to be connected as desired.

When the temperature within the boiler becomes sufficiently high, the fusible members 30 and 30' are melted, thereby opening communication through the opening 11 to the signal and to the fire box, which will cause the signal to be sounded and the fire to be extinguished.

30 Having thus described my invention, I claim:

1. In a low water alarm, a socket member having a longitudinal opening therethrough, a communicating branch passageway leading 35 therefrom, and removable fusible plugs for closing said passageway at each side of the communicating branch.

2. The combination with a crown sheet of a boiler, a socket member having an opening, 40 communicating branch passageways leading therefrom, one passage leading to the fire box to direct steam onto the fire, a signal to which the other passage leads, and fusible means closing said passageways and adapted 45 to melt when the temperature reaches a dangerous degree.

3. In a low water alarm, the combination of a socket member having an opening and communicating branch passageways, one of 50 said passageways leading to the firebox to direct steam onto the fire, a signal to which the other of said passages lead, and fusible plugs fitting in and closing each of said passageways and adapted to melt when the 55 water reaches a dangerous level.

4. In a safety plug, comprising a socket member having a bore extending therethrough, two spaced plugs in said socket member, each having a channel therethrough and fusible means closing said channels.

5. In a safety plug, a socket member having a bore extending therethrough, two removable spaced plugs in said socket member, each having a channel therethrough,

and fusible means removably held by said plugs to close the channels.

6. In combination with the crown sheet of a boiler, a safety plug comprising a tubular socket member, having channels therein, 70 closed by fusible plugs, one channel leading to a signal and the other leading to the fire box.

7. A socket member having two internal plugs, one plug being adjacent one end and 75 the other adjacent the other end, apertures in said plugs communicating with a central chamber and fusible means closing said apertures.

8. A socket member having internal plugs, 80 one plug being adjacent one end and the other adjacent the other end, apertures in said plugs communicating with a central chamber, a channel leading from the chamber to the exterior of the plug and fusible 85 means closing said apertures.

9. A socket member having two internal threads, and having a chamber intermediate said threads, an aperture extending through the wall of the socket member to said chamber, two apertured plugs, each engaging one thread, and fusible means closing said apertures.

10. A socket member having two internal tapering threads, and having a chamber between said threads, an aperture extending through the wall of the socket member to said chamber, and two apertured plugs each engaging one thread, the apertures in said plugs being closed by fusible stoppers held 95 against said plugs.

11. A socket member having two internal tapering threads, and having a chamber between said threads, an aperture extending through the wall of the socket member to said chamber, and two apertured plugs each engaging one thread, the apertures in said plugs being closed by fusible material, one of said plugs being larger than the other 105 plug.

12. A socket member having three tapering threads, apertured threaded plugs adapted to engage the intermediate and one of the end threads, a fusible member secured in place by the apertured plug which engages 115 the intermediate thread, a fusible member resting on the other apertured plug, and means for securing the last mentioned fusible member in place.

13. A socket member having three threads, apertured threaded plugs adapted to engage the intermediate and one of the end threads, a shouldered fusible member secured within the member by the apertured plug which engages the intermediate thread, a shouldered 125 fusible member resting on the other apertured plug, and threaded means for securing the last mentioned fusible member in place.

14. A socket member having two internal threads, a chamber intermediate said threads, 130

a channel leading from said chamber to the exterior of said member, stepped shoulders within said member, a removable, fusible, plug seated on said shoulders, an apertured plug threaded to one of said threads and securing said fusible member in place, a bore extending outwardly from said fusible member, a plug threaded to the other thread, a channel therethrough, a shouldered fusible member seated on said last mentioned plug, a cap engaging said shouldered member and threaded to said last mentioned plug.

15. The combination with a socket member adapted to be applied to the crown sheet of a boiler, of a pair of fusible members removably held therein, said fusible members having the same dimensions, said fusible members closing passageways adapted to lead from the boiler to the fire box and an alarm respectively when the casing is applied to the boiler.

16. The combination of a socket member having an internal thread, a tubular plug

threaded therein and a fusible member seated thereon and held in place by a removable cap, said plug and cap having cooperating parts which center the plug with respect to the cap, said plug, fusible member, and cap, forming a unit removable as a whole, from said casing.

17. The combination of a socket member having an internal thread, a tubular plug threaded therein, a fusible member extending across the end of the tubular plug and having an external boss, and a cap threaded on the plug and having a hole through it normally occupied by the boss on the fusible member, the exterior of the cap being smaller than the threaded portion of the casing.

In testimony whereof, I hereunto affix my signature.

W. S. JACKSON.
